(57) CLAIM

The ornamental design for a light fixture support, as shown and described.

DESCRIPTION

FIG. 1 is a perspective view of the light fixture support showing my new design;

FIG. 2 front elevational view thereof;

FIG. 3 is a rear elevational view thereof;

FIG. 4 is a right side elevational view; the left side being a mirror image thereof;

FIG. 5 is a top plan view thereof; and,

FIG. 6 is a bottom plan view thereof.

The broken line showing of the light fixture is included for the purpose of illustration only and forms no part of the claimed design.
